UNITED STATES PATENT OFFICE

SAMUEL LAMER, OF PITTSBURGH, PENNSYLVANIA, ASSIGNOR OF ONE-THIRD TO
JOSEPH SKRAK, OF PITTSBURGH, PENNSYLVANIA

FOOT LEVER MOTOR

Application filed October 28, 1929. Serial No. 402,982.

This invention relates to a novel foot operated motor for employment in shops and elsewhere where it is desired to drive machinery such as drills, grind stones and in fact any machinery of comparatively small size, the invention having as its primary object to provide a motor which may be operated by the expenditure of a minimum amount of power on the part of the operator, and which may be readily adjusted so as to deliver high power at a low speed or low power at a high speed, so that the motor may be quickly adapted for the driving of different types of machines or mechanisms.

Another object of the invention is to provide a motor of this type in which power is generated by the simple depression of a single foot lever at suitable intervals during the period of time in which the power is needed.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a view in side elevation of the motor embodying the invention.

Figure 2 is a horizontal sectional view taken substantially on the line 2—2 of Figure 1 looking in the direction indicated by the arrows.

Figure 3 is a vertical transverse sectional view taken substantially on the line 3—3 of Figure 1, looking in the direction indicated by the arrows.

Figure 4 is a detail view illustrating a portion of the gearing of the motor.

Figure 5 is a detail view in elevation, illustrating the operating lever and its associated parts.

Figure 6 is a view in side elevation of the fly wheel of the motor.

The mechanism embodying the invention is preferably mounted in a casing 1, which in turn is mounted upon the under side of a

bench 2, upon which the mechanisms, to be actuated by power derived from the motor, may be arranged, the casing being in this manner supported above the floor of the work shop, indicated by the numeral 3. The foot lever is indicated by the numeral 4 and is pivotally mounted at one end as at 5 upon a bracket 6 fixed upon the floor 3, the lever being provided at its opposite end with a foot pedal 7 whereby it may be conveniently depressed by a workman standing opposite the bench 2. A cable 8 is connected at one end to the lever 4 near the foot pedal 7, and is leading upwardly through the bottom of the casing and over a pulley 9 which is mounted at the end of a lever arm 10, which in turn is mounted at its other end as at 11 upon a bracket 12 mounted upon the upper side of the bottom of the casing. From the pulley 9, the cable 8 is lead downwardly and about a small winding drum 13 mounted in a frame 14 upon the under side of the bottom of the casing 1, the end of the cable being connected to the drum and the drum being provided near one end with a disk 15 formed with an annular series of openings 16, and a detent stem 17 is slidably mounted in one side of the frame 14, and is engageable interchangeably in the said openings 16 so that the winding drum 13 may be held stationary at any point in the rotative movement thereof.

In order that the winding drum may be rotated, a hand wheel 18 is fixed upon the other end of the drum shaft and, when a sufficient length of the cable has been wound upon the drum 13 the detent stem 17 is pressed inwardly, against the tension of a spring 19 which is mounted thereon between the side of the casing 14, by a finger knob 20, which is provided at the outer end of the stem, and the engagement of the inner end of the stem in one of the openings in the disk 15 will then serve to hold the cable against unwinding. The stem 17 is held within the opening by tension upon the cable, the spring 19 being insufficient to withdraw the stem until such tension is released. This device is provided for the purpose of varying the extent to which the lever 10 will be moved downwardly upon pressure being exerted upon the foot

pedal 7 of the foot lever 4. The numeral 21 indicates a second lever arm which is pivotally mounted at its inner end as at 22 upon the bracket 12 and the outer end of this arm, 5 which is indicated by the numeral 23, is beveled at its under side thus adapting it to ride downwardly over a rounded nose 24 at the upper end of a pawl 25 which is pivotally mounted as at 26 upon the said lever 10 10 near the pulley 9, it being observed by reference to Figure 1 of the drawings that when the pawl 25 is in engagement with the end 23 of the lever arm 21 and downward movement is imparted to the arm 10, the arm 21 will likewise be moved downwardly about its pivot. 15 In order to determine the point at which the pawl 25 will be disengaged from the end 23 of the lever 21, the said pawl is provided with an arm 27 which extends opposite the lever 20 arm 10 in the direction of the pivot 11 for said arm, the said arm 27 is provided at its rear end with a head 28 projecting downwardly therefrom and engageable with an abutment screw 30 adjustably mounted in the bottom 25 of the casing. A leaf spring 31 is mounted upon the upper side of the lever arm 10 and bears at its free end against the upper side of the arm 27 above the head 28 and it will be evident at this point, and particularly by reference to Figure 5 of the drawings that when the lever 4 is fully depressed the head 29 will engage the upper end of the abutment screw 30 and the arm 27 will be rocked to effect disengagement of the nose 24 from the end of 30 the lever arm 21. The lever arm 10 is guided in its swinging movement by an upright guide 10' mounted upon the bottom of the casing, and a spring 10a is connected with the said arm and tends to swing the same upwardly. 35 When released, the arm 21, in its upward swinging movement, is limited by a stop 29 having a rubber facing to cushion the impact of the arm therewith.

The numeral 32 indicates a shaft which is 40 journalled in the casing 1 and upon which is fixed a pulley 33 to which is connected, at a point in its circumference, one end of a short cable 34, this cable being led downwardly and connected at its lower end as at 35 to the 45 lever arm 21 near the end thereof.

At this point it will be understood that when the pawl 25 is in engagement with the nose 23 and the lever is depressed, the downward swinging movement which is imparted 50 to the arm 21 will result in the rotation of the shaft 32 toward the left in Figure 1 of the drawings due to the unwinding of the cable 34 from the pulley 33. The numeral 36 indicates a large pulley which is likewise 55 fixed upon the shaft 32, and a cable 37 is connected at one end to this pulley as indicated by the numeral 38 and passes to and about a pulley 39 which is mounted upon a shaft 40 journalled in a partition wall 41 60 provided within the casing 1. As the cable

37 is trained over the upper side of the pulley 36 and beneath the pulley 39, rotative movement of the pulley 36 to the left upon depression of the foot lever, as before stated, 65 will effect a rotation of the pulley 39 to the right in Figure 1, and this will effect rotation of a pinion 42, which is likewise fixed upon the shaft 40, and this pinion meshes with a gear 43 mounted upon a shaft 44, likewise 70 journalled in a bearing upon the partition wall 41 below the shaft 40. Inasmuch as the pulley 39 and pinion 42 associated therewith, are rotated to the right in the operation of the lever 4, the gear 43 will be rotated to the 75 left and therefore corresponding rotary motion will be imparted to a ratchet wheel 45 in a corresponding direction and the said ratchet wheel 45 is engaged by a pawl 46, which is pivotally mounted upon a gear 47 in turn loosely mounted upon the said shaft 40, the pawl being yieldingly held in engagement with the ratchet wheel 45 through the medium of a leaf spring 48.

The numeral 49 indicates a coiled spring 80 which is secured at one end as indicated by the numeral 50 to the shaft 40 and at its other end to a cross rod 51, which is mounted between the partition wall 41 and the side wall of a casing 52, which is mounted beside the partition wall. This rotative movement 85 of the gear 47 will therefore effect winding of the spring about the shaft 40 and the gearing, above described, is so proportioned that single downward depression of the foot lever 4 will effect complete winding up of the 90 spring, and it is at this time that the head 28 upon the arm 27 of the pulley 9 will engage the upper end of the abutment screw 30 and result in the release of the lever arm 21 whereupon the spring 49 in unwinding, will 95 impart a reverse rotary motion to the shaft 40.

The numeral 53 indicates a shaft which is 100 journalled in the casing wall 52 and the partition wall 41 and upon this shaft there is 105 fixed a pinion 54 which is in mesh with the gear 47 at one side of said gear. A gear 55 is also fixed upon the shaft 53 and is in mesh with a pinion 56 mounted upon a shaft 57, which is journalled in the partition wall 41 110 and a second partition wall 58 arranged within the casing. Fixed upon the shaft 57 is a fly wheel, which is indicated in general by the numeral 59, and this fly wheel comprises a hub 60 which is fixed to the said shaft 57 and a circular body 61, which is provided at its periphery with a plurality of integrally formed weights 62 which are formed with openings 63 each opening being fitted with a lead filler, as indicated by the 115 numeral 64.

Likewise the body 61 is formed with openings 65 and a filling of lead 68 fills these openings. Openings 67 arranged in an annular series about the axis of the fly wheel, 120

provided for the circulation of air in the rotation of the wheel, thus creating a circulation of air within the casing so as to maintain the parts in suitable cooled condition. 5 The pulley 68' is fixed upon the shaft 79 and a cable 69 is led about this pulley and over a pulley fixed upon a shaft 70, which is mounted pivotally upon the upper side of the bench 2. A shaft 71 is journalled in 10 bearings upon the partition walls 41 and 58 and a pinion 72 is fixed upon this shaft and is in mesh with that side of the gear 47 opposite the side at which the pinion 54, previously described, is located. A pulley 73 is 15 mounted upon one end of the shaft 71, which projects through the partition wall 58 and a cable 74 is trained about this pulley and about another pulley (not shown) upon the shaft 70, it being understood that through the 20 medium of the gear 47, the pinion 72, the pulley 73, the cable 74, and the pulley upon the shaft 70, about which this cable is trained, motion is imparted to the shaft 70. A cable 75 is trained about a pulley 76 fixed upon 25 the shaft 70 and leads to a pulley upon a shaft constituting a part of any mechanism which is to be driven by the motor and which mechanism, as before stated, is to be mounted upon the bench 2. This pulley is driven at 30 such a speed and is so proportioned that it will deliver great power at a relatively low speed.

In order that the motor may deliver less power at a higher speed, a pinion 77 is fixed 35 upon the fly wheel shaft at one end which extends through and is mounted in the partition wall 58, and this pinion meshes with a gear 78 mounted for rotation on a stub shaft 79, which is in turn mounted upon the partition wall 58, a pulley 68' being rotatable with 40 the gear 78 and rotary motion being imparted, from this pulley to a pulley upon the shaft 70.

As previously stated, depression of the foot 45 pedal 7 will move the arm 10 pivotally downward, downward movement of the arm 21 being effected through the dog 25. This operation will rotate the wheel 36 in a counterclockwise direction, while a clockwise rotation will be imparted to the pulley 39 and 50 the shaft 40. Through the medium of the gears 42 and 43, the shaft 44 will be rotated in a counterclockwise direction to wind the spring 49. As soon as the inner end 28 of the 55 dog 25 engages the abutment screw 30, the arm 21 will be released, so that the spring 49 will then be free to unwind. The gear 47 will then rotate in a clockwise direction to 60 drive the pinion 54 and the shafts 53 and 57, while the pulley 68' will be driven at high speed. It is of course understood that when drive is through the pulley 68', the belt 74 will be disconnected. When it is desired to 65 drive through the belt 74, the belt 69 will be

disconnected, increased power and slower speed resulting by the use of the belt 74.

What I claim is:—

1. In a foot operated motor, a shaft from which the power of the motor is to be taken, 70 a shaft geared with the first mentioned shaft, a fly wheel upon the last mentioned shaft, a shaft geared with the fly wheel shaft, a coiled spring connected with the last mentioned shaft and adapted to be wound by the rotation of said shaft in one direction and to constitute a means for driving when the spring is permitted to unwind, and a foot lever operable, in a single depression thereof, to rotate the fly wheel shaft to impart impetus thereto 75 sufficient to fully wind the said spring.

2. In a foot operated motor, a shaft from which the power of the motor is to be taken, 80 a shaft geared with the first mentioned shaft, a fly wheel upon the last mentioned shaft, a shaft geared with the fly wheel shaft, a coiled spring connected with the last mentioned shaft and adapted to be wound by the rotation of each shaft in one direction and to constitute a means for driving the first mentioned shaft when the spring is permitted to unwind, a foot lever operably, in a single depression thereof, to rotate the fly wheel shaft 85 to impart impetus thereto sufficient to fully wind the said spring, and means for automatically returning the foot lever to its initial position after depression. 90

3. In a foot operated motor, a shaft from which the power of the motor is to be taken, 100 a shaft geared with the first mentioned shaft, a fly wheel upon the last mentioned shaft, a shaft geared with the fly wheel shaft, a coiled spring connected with the last mentioned shaft and adapted to be wound by the rotation of said shaft in one direction and to constitute a means for driving the first mentioned shaft when the spring is permitted to unwind, and means for imparting impetus to the fly wheel to fully wind the 105 spring, the said means comprising a lever arm, a pulley upon the second mentioned shaft, a cable connected to the pulley and wound thereon, a pulley, of larger diameter than the first mentioned pulley, to which the cable is also connected, a pulley rotatable with the last mentioned pulley and connected to the lever arm, a second lever arm mounted below the first mentioned lever arm, a latch upon the last mentioned lever arm for engagement with the first mentioned lever arm to connect the two for movement in unison in a direction to unwind the cables, 110 operative connection between the foot lever and the last mentioned lever arm, and means for automatically disengaging the latch from the first mentioned lever arm, when the foot lever has been depressed to its lower limit. 115

4. In a foot operated motor, a shaft from which the power of the motor is to be taken, 120 a shaft geared with the first mentioned shaft, 125

a fly wheel upon the last mentioned shaft, a shaft geared with the fly wheel shaft, a coiled spring connected with the last mentioned shaft and adapted to be wound by the rotation of said shaft in one direction and to constitute a means for driving the first mentioned shaft when the spring is permitted to unwind, and a foot lever operable, in a single depression thereof, to rotate the fly wheel shaft to impart impetus thereto sufficient to fully wind the said spring, the said fly wheel comprising a hub, a web thereon and weighty enlargements at intervals upon the periphery of the web.

In testimony whereof I affix my signature,
SAMUEL LAMER.
